H. J. VENNES

SYSTEM OF CURRENT WAVE TRANSMISSION

Filed May 26, 1919

UNITED STATES PATENT OFFICE.

HARALD J. VENNES, OF NEW YORK, N. Y., ASSIGNOR TO WESTERN ELECTRIC COMPANY, INCORPORATED, OF NEW YORK, N. Y., A CORPORATION OF NEW YORK.

SYSTEM OF CURRENT-WAVE TRANSMISSION.

Application filed May 26, 1919. Serial No. 299,748.

To all whom it may concern:

Be it known that I, HARALD J. VENNES, a citizen of the United States, residing at New York, in the county of New York, State of New York, have invented certain new and useful Improvements in Systems of Current-Wave Transmission, of which the following is a full, clear, concise, and exact description.

10 This invention relates to two-way selective transmission of currents, and particularly to the two-way transmission of modulated currents.

More specifically the invention relates to 15 the prevention of interference between outgoing and incoming transmissions where a current of a given frequency is modulated for transmission in both directions. By the provisions of the invention, selectivity between outgoing and incoming transmissions 20 is obtained even for modulations of the same base-frequency current.

It has been shown that when a high frequency current is modulated by a band of 25 low frequency currents the resultant current may be resolved into a current of the original high frequency and two side bands of frequencies respectively less than and more than the original high frequency. A 30 high frequency carrier wave, when modulated in accordance with speech, for example, possesses these characteristics. It is also known that in order to reproduce the low frequency modulating currents, for example, 35 to receive the speech from the speech modulated current, it is not necessary that both side bands be received, but it is sufficient if one side band is present. It is customary in modulated wave transmission to suppress at 40 the transmitter one of the side bands and the original high frequency wave and to transmit only the remaining side band of frequencies, again supplying the necessary high frequency current at the receiving point 45 from a local source. Heretofore, it has been the practice to transmit in both directions the corresponding side band of the same high frequency, for example, the side band of frequencies less than the original high 50 frequency. For a given low frequency modulating wave, therefore, transmitted over the same high frequency channel in both directions, there will be current of the same frequency fed into the channel and, at the same 55 time, received from the channel at the same

station, and this requires a precise balancing of the transmitter and receiver with respect to the channel, and imposes objectionable limitations upon the relative amounts of energy that are being fed into and derived 60 from the channel. According to the invention one side band of frequencies, for example, the resultant band of frequencies less than the original high frequency is transmitted in one direction, and the opposite side 65 band, in this case of frequencies higher than the original high frequency, is transmitted in the opposite direction, so that at a given station, the transmitted and the received 70 frequencies derived from modulated current of the same high frequency are quite different and the requirement for an exact balance and the objectionable limitations mentioned are obviated.

In the drawing terminal circuits for a 75 system according to the invention are diagrammatically shown for two-way transmission between a high frequency carrier current line HF and each low frequency line LF₁ and LF₂. 80

Each line has a net circuit for balancing for the transmitted frequencies and has the usual conjugate arrangement for transmitting to and from the respective lines. Currents received over the low frequency line 85 LF₁ are impressed through couplings 1 and 2 upon the input of the modulator M₁. Current of carrier frequency f₁ is continuously supplied to the input side of the modulator M₁ from the source 3, which is connected to 90 the terminals of the potentiometer 4. Normally, the effects of this current of frequency f₁ on the two parallel paths of the modulator are equal and neutralize each other in the common output coil 5, so that when no 95 currents are impressed through the coupling 2 upon the modulator, there is no resultant transmission of current of frequency f₁ through the modulator. The currents received from line LF₁, however, cause the potential of the grids 6 and 7 at any instant 100 to be varied oppositely and the impedance of one of the discharge devices 8 or 9 to be increased, while the impedance of the other discharge device is decreased, so that current from source 3 produces a net resultant 105 current-flow through coil 5 as long as the received current from line LF₁ persists. If the frequency or the band of frequencies of the modulating current is indicated by s, the cur- 110

rent in the output coil 5 is a substantially pure modulated current resolvable into frequencies f_1-s and f_1+s . The band filter 10, to which output coil 5 is coupled by means of coil 11, is so proportioned that it transmits freely the currents composing the band f_1+s , but prevents frequencies outside this range from reaching the leads 12, 13. The currents of frequency f_1+s , however, are transmitted through leads 12 and 13 and coils 14 to the high frequency line HF.

At another similar station on line HF, there may be a similar source of current of frequency f_1 , a source of modulating current of frequency s , a modulator similar to M_1 and a filter which will transmit to the line HF only the currents of frequency f_1-s . Currents of these frequencies received at the station indicated in the drawing from over line HF pass through the leads 15 and 16 and through the band filter 20, which is so proportioned as to pass currents of the band of frequencies f_1-s , but to prevent the transmission of currents outside this frequency range. These incoming currents are fed through the coupling 21 to the input of the detector D_1 . The current component of frequency f_1 , which is necessary for the detection of the modulating components comprised in the received currents, is supplied from source 3 which is connected across the potentiometer 22. The action of detector D_1 is the converse of that described of modulator M_1 , that is, it acts to produce in its output coils 23 the low frequency currents which were conveyed over the line HF as modulations of the high frequency f_1 . These detected low frequency currents pass through the filter 24 freely and are supplied over line LF_1 , but any high frequency currents that may have reached the coils 23 are not transmitted by filter 24.

If, as has been the practice heretofore, the filters 10 and 20 were designed to pass the same frequencies, f_1-s , for example, and if this band of frequencies were transmitted in both directions over line HF, any unbalance of the line circuit relative to the circuits including leads 12, 13 and leads 15, 16 would cause part of the relatively large transmitting currents from the leads 12, 13 to feed back into the input of the detector D_1 . By the system of the invention, however, in the event of some unbalance of the line HF as to the transmitting and receiving circuits, currents from the modulator M_1 and filter 10 are of such frequency as not to be passed by filter 20 back to detector D_1 . The system of the invention is thus seen to possess the advantages of the staggered carrier frequency system, in which carrier frequencies used for transmitting in one direction are intermediate those used for the other direction but the invention makes possible a smaller frequency interval between transmissions. The principle utilized in the

invention may be termed staggering of the signaling currents.

In an entirely similar manner, two-way communication between the low frequency line LF_2 and the main line HF may be had. In this case a source 25 of carrier frequency J_2 is provided for supplying the modulator M_2 and the detector D_2 , which may be similar respectively to M_1 and D_1 , and the band filters 26 and 27 are designed to transmit respectively the frequencies f_2+s and f_2-s , the s representing the low frequency or band of low frequency currents carried by line LF_2 .

Separate sources 3 and 25 of high frequency currents have been indicated to simplify the drawing, but in practice it would be usual to derive the different carrier frequencies as harmonics of the output wave of a generator of suitable type located either at the station shown or at a distant point on the line HF.

Only two different two-way channels on the multiplex line HF are provided for in the circuit illustrated, but it is obvious that other channels may be furnished by supplying other high frequency carrier currents and transmitting and receiving circuits. The filters for transmitting to the line HF would be connected to the leads 12 and 13, for instance, similarly to filters 10 and 26, and filters for received currents from the line HF would be connected to leads 15 and 16.

In place of the lines LF_1 and LF_2 , the transmitters and the receivers assumed to be in circuit on said lines might equally well be connected directly to the modulators and detectors, respectively.

While the invention has been described with reference to speech transmission by way of example, it is equally applicable to other kinds of signal transmission, and in fact to selective transmission in general. Also the invention is not to be limited to transmission of currents or waves on wires, but it is evident that an antenna might replace the high frequency line terminal illustrated, and the invention be used for radio transmission.

While the invention has been illustrated and described with reference to a particular circuit arrangement, it is to be understood that it is not to be limited either to the specific arrangement as a whole or to the particular details, but only by the scope of the appended claims.

What is claimed is:

1. The method of two-way transmission of electric energy which comprises modulating at each of a pair of communicating stations a given high frequency wave in accordance with signals and deriving at the respective stations from the wave so modulated, wave components of a given character

for transmission in one direction, and wave components of a different character for transmission in the opposite direction.

2. In two-way transmission of signals by means of a carrier current of a given frequency modulated in accordance with said signals, the method which comprises deriving from the modulated current at the respective communicating stations current components of a given character for transmission in one direction and current components of a different character for transmission in the opposite direction.

3. The method of selective signaling which comprises translating signals into modulations of a sustained high frequency current at each of a pair of communicating stations so that the high frequency current contains components of higher and of lower frequencies and transmitting only said higher frequency components for signaling in one direction, and transmitting only said lower frequency components for signaling in another direction.

4. The method of two-way current transmission which comprises producing at each of two locations a current of a given frequency, varying each said current so that it has components of a higher frequency and components of a lower frequency than said given frequency, and transmitting between said locations in one direction the components of the higher frequencies and in the other direction the components of the lower frequencies than said given frequency.

5. The method of two-way transmission of high frequency current modulated by a band of low frequency currents which comprises transmitting from a station in one direction one side band of the resultant frequencies and transmitting to the station in the opposite direction the other side band of the resultant frequencies.

6. In the transmission of high frequency current modulated by low frequency currents, whereby resultant current of the high frequency and two side bands of frequencies are obtained, the method which comprises suppressing the high frequency component of the modulated wave, transmitting one side band of frequencies in one direction between two communicating stations and transmitting the other side band of frequencies in the opposite direction between the said stations.

7. In a system of two-way transmission of modulated waves of a given base frequency, the method of securing increased selectivity between transmissions to and from a given station which comprises transmitting from said station wave components of a given character derived from modulating current of said base frequency, and receiving from said system at said station current components of a different character derived from modulating current of said base frequency.

8. In a transmission system, stations, sources of current of the same frequency at the respective stations, means cooperating with said sources for producing currents having ranges of frequencies, and means for transmitting a range of said frequencies between said stations in one direction and for transmitting another range of said frequencies in the opposite direction between said stations.

9. In a transmission system, means for modulating waves of a given high frequency at a plurality of stations in accordance with a plurality of low frequencies, means at one of said stations for selectively transmitting a portion of the resulting waves and receiving a different portion; and means at another of said stations for selectively receiving and transmitting portions corresponding respectively thereto.

10. In a transmission system, a line, means for transmitting on said line currents comprising one side band of frequencies of a modulated high frequency current, and means for transmitting in the opposite direction on said line currents comprising the alternate side band of frequencies of a modulated current of the same high frequency.

11. In a transmission system, a line having stations thereon, means at the several stations for producing modulated current of the same base frequency, means at each station for transmitting selectively a portion of said modulated current of different frequency characteristic from that transmitted by another said station.

12. In a multiplex transmission system, a line having a plurality of two-way communication channels each defined by a frequency range obtained by modulating a single base frequency, means for confining transmission in one direction through each said channel to a portion of said frequency range, and means for confining transmission in the opposite direction to a different portion of said frequency range.

13. A transmission line, a source of alternating current, a modulator and a detector supplied with current from said source, a source of modulating energy for said modulator, a band filter for associating said modulator with said line, and a band filter of different frequency characteristic for associating said detector with said line.

14. A line having stations thereon, means at each station for producing current of the same base frequency and for modifying said current by currents of other frequencies, a receiver at each station, circuits for supplying current of given character from said means at a first station through said line to said receiver at a second station, and circuits for supplying current of different frequency characteristic from said means at

1 said second station through said line to said receiver at said first station.

15. In a multiplex signaling system, a line with stations thereon, each station having means for producing high frequency current for said line, and means for detecting said current, and means for modulating said current in accordance with signals so as to produce a pure modulated wave comprising the sum frequencies of a high frequency plus signal frequencies and the difference frequencies of high frequency minus signal frequencies; a filter at one said station for transmitting from said modulating means to said line only the sum frequencies, a filter at the same station for transmitting from said line to said detecting means only the difference frequencies, the detecting means and modulating means at another said station being arranged to cooperate with said filters and with both said means at said one station.
16. The method of two-way transmission of signals between a pair of communicating stations comprising modulating carrier current of a single frequency in accordance with said signals and staggering the components of the modulated wave for transmission in the two directions.
- 30 17. In the two-way transmission of signals used to modulate at the respective communicating stations a carrier current of a single frequency the method which com-
- prises normally suppressing the current of carrier frequency and staggering the components of the modulated wave.
18. A telephone system comprising means for producing voice-modulated currents of the same base frequency at two stations, means for selectively transmitting a range of the resulting frequencies in one direction between said stations and means for selectively transmitting a different range of the resulting frequencies in the opposite direction between said stations.
19. A telephone system including stations, transmitting means at each station for producing voice modulated current of the same base frequency, and means at each station for receiving voice modulated current of said base frequency, a pair of filters at each of the respective stations, one of each pair selective to current of a given frequency characteristic for transmission, and the other selective to current of a different frequency characteristic for reception, the filters at each station having the same frequency characteristics as those at the other station but related to the transmitting and receiving means at the same station in an inverse frequency order as compared with the other station.

In witness whereof, I hereunto subscribe my name this 15th day of May, A. D. 1919.

HARALD J. VENNES.
